US0D1108084S

(12) **United States Design Patent** (10) Patent No.: **US D1,108,084 S**
(45) Date of Patent: ** Jan. 6, 2026

(54) **SHIRT**

(71) Applicant: **RELIVE CO., LTD.**, Sendai (JP)

(72) Inventor: **Masato Yoshida**, Miyagi (JP)

(73) Assignee: **RELIVE CO., LTD.**, Miyagi (JP)

(**) Term: **15 Years**

(21) Appl. No.: **29/957,381**

(22) Filed: **Aug. 13, 2024**

Related U.S. Application Data

(60) Continuation of application No. 29/832,196, filed on Mar. 25, 2022, which is a division of application No. 35/509,039, filed on Apr. 27, 2018 (U.S. filing date under 35 U.S.C. 384), and having an international filing date of Apr. 27, 2018, now Pat. No. Des. 953,702.

(30) **Foreign Application Priority Data**

Oct. 31, 2017 (JP) 2017-024245
Oct. 31, 2017 (JP) 2017-024247

(51) **LOC (15) Cl.** **02-02**

(52) **U.S. Cl.**

USPC **D2/731; D2/840**

(58) **Field of Classification Search**

USPC D2/840, 841, 842, 843, 844, 845, 846,
D2/847, 848, 849, 700, 701, 702, 714,

D2/742, 743, 738, 731, 728

CPC A41D 13/0518; A41D 13/0015; A41D

(74) Attorney, Agent, or Firm — Harness, Dickey & Pierce, P.L.C.

CLAIM

The ornamental design for a shirt as shown and described.

DESCRIPTION

FIG. 1: Front view of shirt;

FIG. 2: Back view of thereof;

FIG. 3: Top view thereof;

FIG. 4: Bottom view thereof;

FIG. 5: Right view thereof;

FIG. 6: Left view thereof;

FIG. 7: Reference front view in a worn state thereof; and,

FIG. 8: Reference back view in a worn state thereof.

The broken lines in the drawings form no part of the claimed design.

1 Claim, 8 Drawing Sheets
